UNITED STATES PATENT OFFICE

2,420,658

DEVICE FOR HANDLING FLANGED OBJECTS

Holger Eiriksson, Groton, Conn.

Application August 20, 1945, Serial No. 611,678

1 Claim. (Cl. 294—87)

(Granted under the act of March 3, 1883, as
amended April 30, 1928; 370 O. G. 757)

1

This invention relates to a device for handling flanged objects, such as oil drums. More particularly, the invention relates to a device for simultaneously handling a plurality of flanged objects, with a minimum of manual manipulation.

It is an object of this invention to provide a device for simultaneously handling a plurality of flanged objects with speed and safety.

Another object of this invention is to provide a device for simultaneously handling a plurality of flanged objects in spaced relationship, so that no contact and resulting damage may occur between them.

Still another object of this invention is to provide a device for simultaneously handling a plurality of flanged objects with a minimum of manual manipulation.

Further objects and advantages of this invention, as well as its construction, arrangement and operation will be apparent from the following description and claim in connection with the accompanying drawings, in which.

Figure 1 is an isometric view of the device of this invention, depending from a crane hook and holding two oil drums.

Referring to the drawings in detail, Figure 1 shows a pair of pendants 11, each of which is formed into an eye at one end and a large bight at the other, suitable for engaging a crane hook. Pendants 11 may be made of any strong flexible material, preferably wire rope. Pendants 11 are enclosed and spaced by eyes at the ends of spreader bar 12, the bight ends of pendants 11 being on the same side of spreader bar 12. Shackles 13 connect rings 14 to the eye ends of pendants 11. Pivotedly mounted on each of rings 14 is a pair of opposed cooperating chime hooks 15. Corresponding chime hooks 15 of each pair are rigidly held in spaced parallel relationship by spacers 16. The handling device is shown as depending from crane hook 17 and as holding two oil drums 18.

The device is utilized in the following manner. The bight ends of pendants 11 are placed about the hook 17 of a crane or similar hoisting or transporting device. Chime hooks 15 are positioned over oil drums 18, and the device lowered until chime hooks 15 extend beyond the chimes of oil drums 18. Crane hook 17 is then raised, and chime hooks 15 engage the chimes of oil drums 18 and grip them securely. Oil drums 18 may then be moved to any desired location. The grip of chime hooks 15 will be secure as long as the oil drums 18 depend from them, and will be automatically released when the oil drums come to

2

rest on some object as crane hook 17 is lowered.

It will be apparent that oil drums 18 are held in parallel spaced relationship as they are suspended from chime hooks 15, the distance between them being determined by the length of spreader bar 12 and spacers 16. On being lifted by the handling device, the drums 18 will automatically assume the spacing thus determined, even though their spacing before being lifted varied somewhat from that, and the assumed spacing will be maintained by the handling device. This spacing precludes contact between the flanged objects, and resulting damage to the objects or their contents.

15 This is particularly advantageous from a safety viewpoint, as workers handling the chime hooks 15 during gripping and releasing of the flanged objects are in no danger of having their hands crushed between them. Fragile objects and objects having a tendency to detonate may be handled easily and safely. The spacing between the objects handled may conveniently be made to correspond to a stowage scheme. For example, the objects handled may be exactly spaced to correspond to notches on stowage racks onto which they are to be lowered.

15 For handling heavy objects, such as oil drums, the device is preferably constructed entirely of steel. The device may be constructed to handle three, four or more objects by merely extending spreader bar 12 and spacers 16, and adding an additional pendant 11, shackle 13, ring 14 and pair of chime hooks 15 for each additional object to be handled. In such case, the lengths of pendants 11 must be adjusted so that the eye ends will fall in a straight line when they are spread by spreader bar 12 and the bight ends are all looped over a single crane hook 17. It will be apparent that since all corresponding chime hooks 15 are rigidly held in parallel spaced relationship, no more personnel is required to place the chime hooks during gripping and releasing operations than would be required to handle a single pair of chime hooks, no matter how many flanged objects the device is constructed to handle simultaneously.

If desired, chime hooks 15 may be hinged directly to spreader bar 12, as by eyes or loops provided on spreader bar 12 for that purpose. In such case, the number of pendants 11 used to suspend spreader bar 12 may be less than the number of pair of chime hooks 15 depending therefrom, one pendant 11 at each end of spreader bar 12 being suitable if spreader bar 12 is sufficiently rigid when carrying a load.

It is to be understood that various modifications and changes may be made in this invention without departing from the spirit and scope thereof as set forth in the appended claim.

The invention described herein may be manufactured and used by or for the Government of the United States of America for governmental purposes without the payment of any royalties thereon or therefor.

What is claimed is:

A handling device comprising two pairs of chime hooks, a ring passing through the ends of each pair of said chime hooks, a shackle connected to each ring, a cable pendant connected to each shackle, a spreader bar having an eye on each end, said cables passing through said

eyes and slidably mounting said spreader bar, and generally parallel rigid bars fixed to one of each pair of said chime hooks.

HOLGER EIRIKSSON.
